UNITED STATES PATENT OFFICE.

FINLEY McARTHUR, OF MONTREAL, CANADA.

WATERING DEVICE.

Application filed November 12, 1923. Serial No. 674,101.

To all whom it may concern:

Be it known that I, FINLEY McARTHUR, a subject of the King of Great Britain, and a resident of Montreal, Canada, have invented 5 certain new and useful Improvements in Watering Devices, of which the following is a specification.

My invention relates to improvements in watering devices, and the object of my improvements is to greatly enhance the efficiency of a drinking fountain for animals, by using improved mechanism for controlling the delivery of water from the reservoir; an easily operable self-sealing cover for the 15 inlet-opening of the reservoir; a housing for the reservoir with movable top, and convenient removable fountain parts including swinging closures therefor.

This object I have accomplished by the 20 means which are hereinafter described and claimed, and which are illustrated in the accompanying drawings, it being understood that changes in the precise embodiment of invention herein disclosed can be made without 25 in the scope of what is claimed without departing from the spirit of the invention.

In said drawings, Fig. 1 is a vertical medial longitudinal section of my improved watering device taken on the broken line 30 1—1 of Fig. 2, and Fig. 2 is a vertical transverse section thereof taken on the broken line 2—2 of said Fig. 1. Fig. 3 is a fragmentary side elevation of the housing, including one of the fountain openings with 35 its swinging closure.

The numeral 1 denotes a water reservoir of cylindrical shape, but which may be of any other shape, and is supported longitudinally and horizontally upon cradle-standards 26 40 fixed on a base-block 39, the latter fitted removably within the lower part of a hollow housing 27 upon the bottom of the latter. This housing has an anticlinal roof or top 28, the inclined parts separated along the 45 median line of the housing and far enough apart at 36 to permit a horizontal top-plate 40 to be fitted closely and longitudinally slidably between them. This plate 40 has an elongated opening of rectangular shape 50 to one side of its middle at 37. The numeral 29 denotes a metal cover-plate which, as shown in Fig. 2 covers the top-plate 40 flatly and has inclined marginal parts which fit upon the upper parts of the inclined roof members 28, and is longitudinally slidable 55 also. At one end of the plate 40 is a depend-

ing arm 30 with an angularly directed extremity 31 receivable into a hole 32 in the end of the housing to limit movement of said plate in one direction. An angle-plate 60 38 is dependingly fastened to the under face of the top-plate 40 to limit the movement of this plate in an opposite direction. The plates 29 and 40 are secured together to move as one as indicated by the dotted lines 65 in said Fig. 1.

A metal loop 33 is fixed in the right-hand part of the superposed plates 29—40 and upon it is pivotally mounted one end of a bent hasp 34 slotted to receive a pin 35 fixed 70 in the end wall of the housing, to hold said plates in their closed position.

The reservoir 1 has in its top near one end and below the opening 37 an opening covered by an apertured plate 4 secured to the reservoir and this plate has its aperture in registration with said opening and has an annular raised rim 5 therearound spaced from a higher concentric rim 2 thereon, and in the trough between these rims is removably fitted a rubber gasket 6 to project a little above the rim 5 but below the outer rim 2. Upon opposite outer sides of the outer rim 2 are cam-projections 3 as shown 75 best in Fig. 2. The numeral 9 denotes a bar 80 positioned diametrically across the rim 2, and has depending end parts whose extremities 10 are bent inwardly and have cam faces to engage the cam faces of the cam projections 3 to releasably lock the bar 9 85 upon the rim 2. The numeral 7 denotes an 90 imperforate disk which is positioned above the rim 5 to engage compressingly the gasket 6 to provide a tight closed joint which will not admit air. The disk 7 has a central stem 8 whose diminished upper end is secured 95 within a hole in the middle of said bar 9, so that when the bar cam-ends 10 are engaged with the cam projections 3, the disk 7 is held tightly and compressingly against 100 said gasket 6.

A shallow elongated pan or water receptacle 23 is positioned within said housing a short distance below the reservoir 1 and transversely to the length of the latter, has sloping end parts and downturned end margins 48 which are passed releasably through openings in the side walls of the housings to thus support or suspend the receptacle at a proper relation to the reservoir. 105

The numeral 25 denotes hoods which have their lower ends extending into the recep-

tacle 23, and are inclined upwardly and outwardly to have their outer margins 45 passed through said side wall openings and to engage the outer face of the housing 5 around the openings, and these hoods may be removed outwardly through said openings when desired. The hoods inclose drinking founts for animals when they push their heads through the openings.

10 Closure-plates 46 are provided for said openings and have holes 49 in their tops to receive the hooks 47 on the upper rim 45 to suspend the closures swingingly and keep dust and insects from passing into the hous- 15 ing through the openings, but animals may push these closures in to obtain access to the water in said founts as indicated by the dotted lines in said Fig. 2.

The hoods may be releasably locked in 20 their positions by means of pivoted keepers 43—42 swung over the top rims 45.

The reservoir 1 has a medially located bottom opening 21 and a plate 20 is fixed to the outer wall of the reservoir and has an 25 opening communicating with said opening 21 in which is closely sealed a short vertical tube 22 having a delivery hole 41 in one side of its lower part which dips within the water contents of the receptacle 23. The 30 upper end of the tube 22 extends into the interior of the reservoir 1 and has a coned valve-seat 19 to seat and fit a coned valve-head 18 fixed upon the lower part of a vertically disposed rod or stem 16. The upper 35 end of this stem is forked to receive pivotally on a cross pintle 17 the forked extremity of a lever 13 which is medially pivoted at 14 upon a downwardly widened hanger 15 from the top inner wall of the reservoir. 40 The free end of this lever is bent rectangularly upwardly at 12 and has a hemispherical head 11 which movably engages the lower face of the disk closure 7 when the latter is closed. A vertically disposed open 45 end tube 24 traverses the reservoir to nearly the top of the latter, and has its lower end extend nearly to the bottom of the receptacle 23, below the hole 41 in the delivery-tube 22, so that when the level of the water falls in 50 the receptacle 23 below the hole 41 and the lower end of said tube 24, air will enter the latter and pass into the upper part of the reservoir.

When the sliding-cover parts 29—40 have 55 been moved to the left to uncover the disk cover 7, the cover 7 may be removed to fill the reservoir 1, by turning the bar 9 to release its cam ends 10 from the cam projections 3. This releases the lever 12, so that 60 the weighted valve-head 18 may subside enough to seat it on the valve-seat 19 until the reservoir is filled, when replacing the cover will press down the lever 12—13 lifting the valve-head so that water may be delivered into the receptacle 23 to a height at

the upper part of the hole 41 or just above it to close it and maintain this level as the water is drunk out by animals.

It will be seen that the operation of this device after being assembled, is automatic 70 after the cover 7 is closed after filling the reservoir until the water contents are exhausted, at which time the simple arrangement of the sliding top 29—40 permits a re-filling of the reservoir in a minimum of 75 time.

Having described my invention, what I claim as new, and desire to secure by Letters Patent, is:

1. A watering device, comprising a closed 80 reservoir having an inlet-opening in its top with a raised rim, the latter having cam-projections upon its outer wall, flexible air-proof sealing-means mounted on said rim, an imperforate closure-plate mounted upon 85 said sealing-means, a clamping-device connected to said closure-plate and having inwardly-bent extremities formed with cams to slidingly engage said cam-projections to clamp said closure-plate compressingly upon 90 said sealing-means, said reservoir having a bottom opening in which is fitted an open-end delivery tube having in its end within the reservoir a coned valve-seat, a valve-head coned to fit said valve-seat and having an 95 upwardly-directed stem, a lever in said reservoir pivotally supported medially and having one extremity pivoted to the upper end of said valve-stem, the other end of said lever being bent upwardly angularly to terminally contact with the lower face of said closure-plate when closed upon said sealing-means to thus lift the valve-head from its seat, the weight of said valve-head and stem being sufficient to lower them to close the 100 valve-head upon its seat when the said closure-plate is removed.

2. A watering device, comprising a closed 105 reservoir having an inlet-opening in its top provided with a raised rim having engaging-means thereon, a flexible gasket fitted on said rim, an imperforate closure-plate mounted upon said gasket, a bar medially 110 rockingly connected to said closure-plate and having engaging-means on its extremities 115 for detachably coengaging with the engaging-means on said rim to compress the closure-plate against said gasket, said reservoir having a bottom delivery outlet, a valve for controlling said outlet positioned within the 120 reservoir, a lever within the reservoir mounted pivotally with one end linked to said valve and its other end contacting with said closure-plate when closed to hold the valve open, an open top receptacle positioned 125 below said reservoir to receive water from said delivery-outlet, and an air-tube having its upper open end within the upper part of said reservoir with its open lower end projecting through the bottom of the reservoir 130

into said receptacle below said delivery-outlet.

3. A watering device, comprising a closed reservoir having an inlet-opening in its top with a raised rim having oppositely directed cam projections, a removable closure within said inlet-opening having coacting cam projections releasably engaging the first-mentioned cam projections, means between said closure and the reservoir for packing and making the joint thereof air-proof, said reservoir having a bottom delivery-outlet, valvular means for controlling said delivery-outlet, an open top receptacle positioned below said delivery-outlet and having its opposite ends extending sidewise beyond the

reservoir, a housing about said reservoir and receptacle having an opening in the top and a ported sliding cover for said opening, means for limiting the scope of movement of said cover, said housing having wall openings communicating with the end parts of said receptacle, hoods removably mounted in said receptacle ends to open coterminally with and releasably engage the walls of said openings, and swinging closures for said wall openings yieldingly movable inwardly into said hoods to permit access to the contents of the receptacle from without.

Signed at Cedar Rapids, Iowa, this 27th day of October, 1923.

FINLEY McARTHUR.
